[57] **CLAIM**

The ornamental design for a dispenser for surgical sutures, substantially as shown and described.

DESCRIPTION

FIG. 1 is a front view of my design for a dispenser for surgical sutures;

FIG. 2 is a rear view thereof;

FIG. 3 is a top view thereof;

FIG. 4 is a side view thereof;

FIG. 5 is a cross-sectional view of FIG. 4 taken along the vertical center line of FIG. 1;

FIG. 6 is an exploded view of FIGS. 1 to 4 showing the reel and disc portions separately;

FIG. 7 is an alternative opaque reel of the reel shown in FIG. 6.

The lettering in broken lines in FIG. 2 is for illustrative purposes only.

FIG. 1
